UNITED STATES PATENT OFFICE.

AARON P. STORRS, OF OWEGO, NEW YORK.

DESIGN FOR A CANOPY-SUPPORT.

SPECIFICATION forming part of Design No. 32,573, dated April 24, 1900.

Application filed January 16, 1900. Serial No. 1,698. Term of patent 7 years.

To all whom it may concern:

Be it known that I, AARON P. STORRS, a citizen of the United States, residing at Owego, in the county of Tioga and State of New York, have invented a certain new and original Design for a Canopy-Support, of which the following is a specification.

My invention relates to a design for "canopy-supports," by which term I have reference to a device for supporting a disk-like mica canopy above the chimney of a lamp or other burner.

My new and original design is illustrated in the accompanying drawings, in which—
Figure 1 is a perspective view; Fig. 2, a plan view; Fig. 3, an end view, and Fig. 4 a side view.

In all of the above views like parts are designated by the same numerals of reference.
The leading feature of my design consists of a canopy-support having an essentially-

horizontal member, a shorter inclined member connected thereto, and a coil at the free end of each of said members.

In the drawings the support 1 is provided with an essentially-horizontal member 2 and a shorter inclined member 3. The lower end of the inclined member 3 is formed in an essentially-vertical spiral coil 4. I illustrate the horizontal member 2 as being formed at one end into an essentially-horizontal coil 5.

Having now described my invention, what I claim as new, and desire to secure by Letters Patent, is—

The design for a canopy-support herein shown and described.

This specification signed and witnessed this 12th day of January, 1900.

AARON P. STORRS.
